HIGH-FREQUENCY TERMINAL

John R. Woodyard, Berkeley, Calif., assignor to
 The Sperry Corporation, Great Neck, N. Y., a
 corporation of Delaware

Application December 14, 1946, Serial No. 716,210

4 Claims. (Cl. 178—44)

1

The present invention relates generally to ultra high frequency vacuum tube structure and, more specifically, to vacuously sealed high frequency lead-ins for such tubes. The invention is illustrated as applied to ultra high frequency electron discharge devices utilizing hollow or cavity resonators and, more particularly, to terminal posts or high frequency couplings to or from such resonators. The present application is a continuation-in-part of copending application Serial No. 428,682, for High Frequency Tube Structure, filed January 29, 1942, now Patent No. 2,414,785.

In ultra high frequency electron discharge devices using cavity resonators, it has become usual practice to utilize the walls of the cavity resonator as part of the vacuum envelope for the device. To couple ultra high frequency energy to or from these devices, it has also been known to utilize coaxial line couplings or terminal posts having an outer conductor communicating with the resonator cavity through an opening in the wall thereof and having an inner conductor connected to the outer conductor by a coupling loop at the end thereof which is positioned within the space enclosed by the resonator and which accordingly couples the output line to the electromagnetic field within the resonator. To maintain the evacuated condition of the resonator and of the device, it has become usual to provide a vitreous vacuum seal between the inner and outer conductors of this coaxial line terminal post. Structure of this type, for example, is shown in Fig. 7 of Hansen et al. Patent No. 2,311,658, issued February 23, 1943.

In the past, trouble has been experienced in many instances with this seal between the inner and outer conductors of the coaxial line terminal post. For connection of the electron discharge device to other circuits, it is necessary, of course, to couple suitable concentric lines or other high frequency conductors to the terminal posts of the discharge device. When such couplings are not accurately formed or when the seal from the terminal post is not accurately made, misalignment between the inner conductor of the terminal post and the inner conductor of the connecting line causes strains to be transmitted to the seal, which is usually in the form of a glass bead. Such strains, if severe enough or repeated often enough, frequently result in breaking the seal, with resultant loss in vacuum. Also, the normal handling of such devices may cause the inner conductor of the terminal post to accidentally come into contact with other objects.

2

The shock of such impact frequently cracks the seal and renders the device useless.

According to the present invention, provision is made to render such device and seals more rugged, both for ordinary handling and for connection to other circuits. For this purpose an enclosing sleeve is placed about the terminal post to prevent the tip of the inner conductor from being exposed and susceptible to impact with external objects. Also, to minimize the effect of such impact, the inner conductor of the terminal post is formed with a section of restricted cross-sectional area which may readily bend. Such bending will occur to absorb the shock of impact with an external object or to absorb the effect of misalignment with the lines coupled to the terminal post and will prevent strains from being transmitted to the seal. In this manner a highly rugged high frequency lead-in and seal, useful in coaxial or concentric line terminal posts, are provided, and the breakage formerly encountered has been substantially minimized.

Accordingly, it is an object of the present invention to provide novel high frequency lead-ins and seals affording improved ruggedness for use with tube structures.

It is another object of the present invention to provide improved concentric or coaxial line terminal post means for ultra-high-frequency evacuated cavity resonators.

It is another object of the present invention to provide improved concentric line terminal posts for evacuated cavity resonators, and provided with means for preventing damage to the seal thereof due to physical impact.

Other objects and advantages of this invention will become apparent from the specification, taken in connection with the accompanying drawings wherein the invention is embodied in concrete form.

In the drawing,

Fig. 1 is an elevational view, partly in cross-section, of an electron discharge device embodying the improved high frequency lead-in and seal of the present invention.

Fig. 2 is an enlarged sectional view of the high frequency lead-in and seal.

The present invention is illustrated as used in a single-resonator electron beam velocity-modulating tube structure of the reflex type as disclosed in Fig. 2 of Patent No. 2,250,511 for Oscillator Stabilization System, granted July 29, 1941 to Russell H. Varian and William W. Hansen.

Referring to the drawing, the cathode structure of this tube consists of emitter surface 1

which may be of the oxide-coated type heated by a resistance heater 2, emitter 1 being coaxial with and surrounded by a focusing shield 3 which is illustrated as containing a woven mesh grid 4 that may act as a control or modulator grid as desired. Electrons from emitter 1 are projected in a beam of round cross-section through an accelerating and field-smoothing grid 5 by means of any suitable unidirectional voltage (not shown) applied between cathode 1 and a plate 6. Plate 6 is provided with a cylindrical neck portion 7 in which grid 5 is mounted and which serves to provide a field-free space in which the electron beam travels toward and through entrance grid 8 of a hollow conducting resonator 9. Resonator 9, as shown, has a reentrant portion 10, a flexible end wall 11, an outer cylindrical wall 12, and rigid flat end wall 13 opposite wall 11. End wall 13 of resonator 9 is apertured and carries a grid structure 14 concentric with and close to grid 8. Grids 5, 8 and 14 may have any desired form, as shown in our above-mentioned parent application No. 428,682, now Patent No. 2,414,785. Spaced concentric to grid 14 and close behind it is a reflector electrode 18 which may be dish-shaped as shown. Reflector 18 is supported by conductor 19 which passes through glass end bell 20, which is supported by and sealed to end wall 13 of resonator 9 in the conventional manner.

In operation, the electron beam emitted from cathode 1 is projected through accelerating and smoothing grid 5 and through entrance grid 8 into resonator 9. In this resonator 9 the beam suffers recurrent velocity changes or is velocity modulated by an oscillating electric field existing between grids 8 and 14. The beam travels out through exit grid 14 and is reflected back through grid 14 by a potential applied to reflector 18 approximately equal to that of the cathode 1. The reentry of the beam into resonator 9 takes place after recurrent bunching or density modulation of the beam has taken place. The grouped beam then gives up energy to the alternating electric field between grids 14 and 8, thus maintaining oscillations in resonator 9.

End plate 6 and end wall 13 are provided with flange extensions 30 and 29, respectively, which extend perpendicularly to the axis of the tube. Flange 29 is provided with three screws 37 which may be spaced 120° apart near the periphery of this flange 29, having slotted ends facing away from flange 30. Screws 37 are provided on their inner ends with socket joints 38 for receiving the ends of cylindrical struts 39, which struts have hemispherical ends 40 bearing in sockets 41 in flange 30. Struts 39 are forced to bear with the proper force against flange 30 by springs 42 which are under tension between flanges 29 and 30 and may be spaced 120° apart near the peripheries of these flanges intermediate the screws 37. Rotation of screws 37 varies the distance between grids 8 and 14, thereby changing the natural frequency of resonator 9 and the output frequency of the device.

Resonator 9 is provided with coaxial line terminal posts or elements 21 and 22 emerging from resonator end wall 13. These terminal posts include a tube or tubular portion 23 which may be of "Kovar" an alloy of approximately 30% nickel, 15% cobalt and 55% iron described in Patent No. 1,942,290 or other metal readily sealable to glass and forming the outer conductor of the concentric line terminal post. Tube 23 is soldered or brazed into an aperture in wall 13

of resonator 9. An inner rod 24 concentric with tube 23 serves as the inner conductor of the terminal post. It may be of tungsten and is positioned coaxially of tube 23 by a glass vacuum-tight seal or insulating plug 25. The inner end 26 of rod 24 supports one end of coupling loop 27 electrically integral therewith, the other end of loop 27 being welded to the inner end of tube 23. The outer end of inner conductor 24 is conical, as shown at 50, to facilitate fitting of the inner conductor of a concentric line to be attached thereto, which is usually formed with a recess cooperating with tip 50.

Slightly above the outer surface of glass seal 25, rod 24 has a relieved or constricted section 28. It is found that without the small diameter section 28, if the outer end 50 of rod 24 is accidentally hit, glass seal 25 would break near rod 24. However, with the constricted section 28, this section merely bends if accidentally hit, and the seal 25 is not broken. To minimize the chances of such accidental striking, outer conducting tube 23 is surrounded by a collar 21 which extends above the insulating seal 25 and around tip 50. Collar 21 also is attached to tube 23 adjacent seal 25 and serves to reinforce tube 23.

Concentric line terminal posts such as 21 and 22 may also be placed so that they project radially from the cylindrical wall 12, if desired, rather than from end wall 13 of the resonator.

The present invention thus provides a sealed high frequency lead-in for vacuum tubes which is rugged and stands up well under widely varying conditions of use. This lead-in is especially useful for high power leads, since it is possible to use the large diameter conductors necessary to prevent heating at the seal which might impair its effectiveness, while at the same time making it possible to minimize the shock susceptibility formerly associated with large and necessarily rigid lead-ins.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A concentric line terminal post for hollow resonators comprising an outer conducting tube adapted to have its inner portion projecting into the apertured wall of a hollow resonator, the outer portion of said tube having a reinforcing collar thereon, an inner conductor positioned concentrically within said outer tube and having a loop connection between its inner end and said outer tube for projecting into the interior of the resonator for coupling with the field thereof, a vitreous seal between said inner conductor and said outer conducting tube positioned outwardly of said loop, said inner conductor having a readily bendable portion outwardly of said seal, the outer end of said reinforcing collar and of said inner conductor terminating in a substantially common plane.

2. A concentric line terminal post for hollow resonators comprising an outer conducting tube joined to the wall of a hollow resonator and communicating with the interior thereof, the outer portion of said tube having a reinforcing collar thereon, an inner conductor positioned concentrically within said outer tube and having

a coupling connection for coupling with the high frequency energy within said resonator, a vitreous seal between said inner conductor and said outer conductor, said inner conductor having a constricted portion outwardly of said seal and within said reinforcing collar whereby unexpected forces applied to said terminal post are prevented by said collar from injuring said seal, said constricted portion also aiding in the protection of said seal by enabling the ready bending of said inner conductor under stress.

3. A coaxial line seal comprising a conductive tubular portion, a conductive rod extending therethrough, a reinforcing collar around a part of the tubular portion, and an insulative plug within the part of the tube surrounded by the collar, said plug being sealed to both the tubular portion and to the rod.

4. A concentric line terminal post comprising an outer conducting tube, an inner conductor positioned concentrically within said outer tube, an insulating seal between said inner conductor

and said outer tube and supporting said inner conductor relative to said outer tube and sealing the inward portion of the interior of said outer tube from the outward portion thereof, said tube having a reinforcing collar surrounding said seal and extending outwardly thereof and overlying the free end portion of said inner conductor, whereby shocks applied to said terminal post will be prevented from appreciably jarring said inner conductor thereby protecting said seal against fracture.
